US0D1088727S

(12) **United States Design Patent** (10) **Patent No.:** **US D1,088,727 S**
(45) **Date of Patent:** **** Aug. 19, 2025**

(54) **MUG INSERT**

(71) Applicant: **Vinglace LLC**, Houston, TX (US)

CN 201718942 U 1/2011
CN 304269009 9/2017

(72) Inventor: **Colton Bryan Haas**, Houston, TX (US)

(Continued)

(73) Assignee: **Vinglace, LLC**, Houston, TX (US)

(**) Term: **15 Years**

(21) Appl. No.: **29/964,406**

(22) Filed: **Sep. 23, 2024**

Related U.S. Application Data

(63) Continuation of application No. 29/919,138, filed on Dec. 1, 2023, now Pat. No. Des. 1,043,240, which is (Continued)

(57) **CLAIM**

The ornamental design for a mug insert, as shown and described.

DESCRIPTION

FIG. 1 is a perspective view of a mug insert showing my new design;

FIG. 2 is a left elevation view of the mug insert of FIG. 1; FIG. 3 is a front elevation view of the mug insert of FIG. 1; FIG. 4 is a right elevation view of the mug insert of FIG. 1; FIG. 5 is a rear elevation view of the mug insert of FIG. 1; FIG. 6 is a top plan view of the mug insert of FIG. 1; FIG. 7 is a bottom plan view of the mug insert of FIG. 1; and, FIG. 8 is a cross-section view of the mug insert along line 8-8 of FIG. 6.

The broken lines consisting of dashes show an environment that forms no part of the claimed design.

1 Claim, 7 Drawing Sheets

Related U.S. Application Data

a continuation of application No. 29/814,278, filed on Nov. 4, 2021, now Pat. No. Des. 1,008,730.
